CHARLES W. SIEVERT, OF LOS ANGELES, CALIFORNIA, ASSIGNOR OF ONE-HALF TO
ALBERT H. SIEVERT, OF LOS ANGELES, CALIFORNIA.

FLANGING-MACHINE.

1,124,963.

Specification of Letters Patent. Patented Jan. 12, 1915.

Application filed February 23, 1911. Serial No. 610,326.

To all whom it may concern:

Be it known that I, CHARLES WILLIAM SIEVERT, a citizen of the United States, residing at Los Angeles, county of Los Angeles, State of California, have invented new and useful Improvements in Flanging-Machines, of which the following is a specification.

This invention relates to improvements in my invention entitled flanging machines for which Letters Patent were issued to me on the 1st day of December, 1908 and bearing No. 905,376; and the invention relates to a flanging machine for making flanged tops 15 of sheet iron for tanks or similar articles, and to a machine in which the flange is formed in small sections at one time, rather than the whole flange formed at one operation; and the objects of my invention are 20 mainly to provide a means for making a perfectly smooth flange with a clean edge, and to provide a machine which may be easily operated by hand or by power.

My invention consists more particularly 25 in the peculiar formation of the inner and outer formers and of the clamping foot which holds the disk of metal on the former. These configurations are so made that the edge of the disk is drawn down into a perfectly smooth flange in the manner which 30 will hereinafter become apparent.

I attain these objects by the mechanism illustrated in the accompanying drawings, in which—

35 Figure 1 is a vertical longitudinal section of my improved flanging machine. Fig. 2 is a horizontal plan section taken on line 2—2 of Fig. 1. Fig. 3 is a detail cross section taken on line 3—3 of Fig. 1.

40 A base or frame 5 is provided for the machine, being of suitable configuration, for the support of the parts to be hereinafter described and of sufficient weight and strength to withstand any pressure which 45 may be applied thereto. At its front the base carries a supporting table 6 provided with an aperture 7 near the center of its upper face. A lug 8 on the lower face of former table 9 fits loosely into aperture 7.

50 Former table 9 extends out away from the machine and is provided with a series of apertures 10 (or slots may be substituted) in which pin 11 is adapted to be placed. Pin 11 forms the center on which disk 12 55 is swung, the disk being provided with a

punched hole in its center for this purpose. For a disk of given diameter pin 11 is so placed that the edge of the disk overhangs the inner forming face 13 of former 14, as is shown in Fig. 2. Former 14 is made integral with former table 9 and the whole structure is loose upon supporting table 6. An adjustable screw 15 is mounted in frame 5 immediately below table 6 and presses against the rear face of former 14 at 16, holding the former up into the machine. The front, or forming, face of the former 14 is curved about a vertical axis as is shown in Fig. 2. This curve corresponds to the average curve of flange of the disks operated on by that particular former. For instance, its curvature can only correspond to the flange curvature of a flange centering where pin 11 is now shown in the drawings; but its correspondence to the curvatures of flanges centered on the other apertures 10 is close enough to give good practical results. Thus, in practice, each former is made to take flanges of diameters varying within certain limits found by practice to be best.

The upper face of former 14, and of table 9 adjacent the former, is curved as is shown at 20 in Fig. 3. The lower face of a clamping foot 21 is also curved as shown at 22 in Fig. 3. Foot 21 is mounted on a lever 23 pivoted at 24 to frame 5. The other end of the lever is provided with an adjustable follower 25 engaging with a cam 26 mounted on shaft 27. Shaft 27 is the main operating shaft of the machine and carries handles 28 on each end. These handles 28 may be, and preferably are, joined together outside the machine so as to form a single handle for convenience in operating. Removably mounted on cam 26 is an outer former 29 having a forming face 30 of double curvature. In the direction parallel to the movement of the former, or transverse to shaft 27, face 30 is convex, while in the direction transverse to its movement, or parallel to the shaft, the face 30 is concave. This is clearly shown by the two sections. The concavity of face 30 is not quite so great as the convexity of face 13 of inner former 14, so that the two faces only come together along a central line. Inner former 14 being loose, except for abutting screw 15, it is free to move to adjust itself to any position into which it is forced by contact with outer former 29.

In operating my machine, a flat disk of metal is placed upon table 9 in the position indicated, outer former 29 and handle 28 being in the position shown in dotted lines 5 in Fig. 1. Handle 28 is then brought down toward the position shown in full lines. The first action of the machine is to bring foot 21 down on plate 12 and to force the engaged portion of the plate into the form shown in 10 Fig. 3. This is accomplished by means of cam 26 coming into engagement with the follower 25. The follower will be held in the position shown by surface 35 on cam 26, which surface is concentric with shaft 27. 15 After the plate has been thus clamped in position the lower portion 37 of face 30 of outer former 29 comes into contact with the edge of the plate projecting beyond the face 13 of inner former 14. As the handles are 20 brought down the edge of the plate is gradually forced to the position shown in Fig. 1. When, at last, the formed flange is forced up against face 13, face 30 of outer former 29 has moved up solidly against the outer face 25 of the flange. This is provided for by making face 30, at the point shown in contact with the flange in Fig. 1 of less curvature than at the point 36, making the face at that point almost flat; and also by placing shaft 30 27 below the plane of the plate so that the circular movement of the outer former brings it closer to the inner former at its upper edge. It is to be understood that the form given to disk 12, as shown in Fig. 3, is only 35 a temporary one, that is, that portion of the disk adjacent the formers is temporarily forced into concavo-convex shape during the flanging operation, only a small portion of the disk and flange are affected at any given 40 moment and when the foot 21 is released the disk immediately resumes its former flat form. The handle is then raised and the plate turned through an appropriate angle and the operation repeated. This is done 45 as many times as is necessary to completely flange the plate.

It will be seen that the circumference of the flange edge is much less after formation than before formation and that consequently 50 a larger amount of material must be forced into the flange than is present in the normal plate. The curvature of the foot 21 and former 14 accomplishes this. By curving the plate in the direction shown, with the 55 concavity toward the side on which the flange is to be formed, the periphery of the flange is thereby compressed while it is being formed and the material is forced into the flange without any folds or wrinkles. 60 This curvature depends upon the size of the plate and the width of the flange, but for a given diameter of plate and width of flange

there is always a radius of curvature which will enable a perfectly smooth flange to be formed.

Having described my invention, I claim:

1. In a flanging machine, the combination with a lower former having a convex flange forming end face and a convex upper clamping face near said end face and otherwise 70 level, a clamping member having a lower concave clamping face to dish the sheet to be flanged near its edge during the flanging operation and means coöperating with the former for forming a flange on a sheet 75 clamped between the clamping member and former.

2. In a flanging machine, the combination with an outer former having a convex upper face and a convex inner end face of a presser member having a concave under face for co-operation with the convex upper face of said former, a cam member, a former movable with said cam member, a manually operable member connected to said cam member, the last named former having a concave outer face, initial movement of the manually operable member serving to bring the presser member into forcible contact with the convex upper face of the inner former and continued movement of said manually operable member serving to move the cam carried former across the end face of the inner former.

3. In a flanging machine, the combination 95 of an anvil having an edge about which the edge of a plate is turned to form a flange, the work engaging face of the anvil being convex about an axis transverse to the work turning edge, a combined work clamp and 100 bender comprising a foot with a concave face adapted to coöperate with the anvil to bend and clamp the plate, and means for turning the edge of the bent plate toward its concave side around the edge of the anvil to 105 form a flange.

4. In a flanging machine, the combination of an anvil having an edge about which the edge of a plate is turned to form a flange, the work engaging face of the anvil being 110 convex about an axis transverse to the work turning edge, a single means for clamping a plate on the convex face of the anvil and for bending the plate on the anvil, and means for turning the edge of the front plate toward its concave side around the edge of the anvil to form a flange.

In witness that I claim the foregoing I have hereunto subscribed my name this 14th day of February, 1911.
